(57) **CLAIM**

The ornamental design for a BNC cap assembly, as shown and described.

DESCRIPTION

FIG. 1 is a top, back, right side perspective view of a BNC cap assembly according to a first embodiment;

FIG. 2 is a back elevational view thereof;

FIG. 3 is a front elevational bottom plan view thereof;

FIG. 4 is a left side elevational view thereof;

FIG. 5 is a right side elevational view thereof;

FIG. 6 is a top plan view thereof;

FIG. 7 is a bottom plan view thereof; and

FIG. 8 is a top, back, right side perspective view thereof, shown connected with a disclaimed BNC plug with which the BNC cap assembly may be integrated.

FIG. 9 is a top, back, right side perspective view of a BNC cap assembly according to a second embodiment;

FIG. 10 is a back elevational view thereof;

FIG. 11 is a front elevational bottom plan view thereof;

FIG. 12 is a left side elevational view thereof;

FIG. 13 is a right side elevational view thereof;

FIG. 14 is a top plan view thereof;

FIG. 15 is a bottom plan view thereof; and,

FIG. 16 is a top, back, right side perspective view thereof, shown connected with a disclaimed BNC plug with which the BNC cap assembly may be integrated.

Broken lines included in the figures show portions of the BNC cap assembly that form no part of the claimed design. Broken lines in FIG. 16 show environmental structures that also form no part of the claimed design.

1 Claim, 12 Drawing Sheets
